UNITED STATES PATENT OFFICE.

WILLIAM W. JACKSON, OF PHILADELPHIA, PENNSYLVANIA, ASSIGNOR TO THE MACKELLAR, SMITHS & JORDAN COMPANY, OF SAME PLACE.

DESIGN FOR A FONT OF PRINTING-TYPE.

SPECIFICATION forming part of Design No. 20,702, dated April 28, 1891.

Application filed February 6, 1891. Serial No. 380,504. Term of patent 7 years.

To all whom it may concern:

Be it known that I, WILLIAM W. JACKSON, a citizen of the United States, and a resident of Philadelphia, Pennsylvania, have invented

5 a Design for a Font of Type, of which the following is a specification.

My design for a font of type is clearly illustrated in the accompanying typographical impression, in which is shown the upper case and 10 lower case of type, together with the numerals.

The general character of the design is that of a solid fancy type, the special features being the double cross-lines and the finishing of some of the letters, giving the peculiar effect clearly 15 shown in the accompanying impression. The face of each letter is elongated vertically and is solid. The cross-bar of the letter A is composed of two lines slightly curved, and the cross-bar of the letter H is likewise slightly curved and 20 arranged above the center of the letter, while the lower portions of the letters C, J, L, and S finish in a scroll. Each corner of a square letter projects to a point or fin, as clearly shown, and the lower line of the upper loop of the letter B is inclined, as well as the lower line of the loop of 25 the letters P and R. The letters of the lower case are in keeping with the letters of the upper case. The numerals are also in keeping with the letters of the upper case.

I claim—

30 The design for a font of type, substantially as herein described, and as shown in the accompanying typographical impression.

In testimony whereof I have signed my name to this specification in the presence of 35 two subscribing witnesses.

WM. W. JACKSON.
